UNITED STATES PATENT OFFICE

JOHN BATES, OF BEAUMARIS, VICTORIA, AUSTRALIA

HAND OPERATED LOAD LIFTING DEVICE

Application filed November 28, 1928, Serial No. 322,430, and in Australia September 25, 1928.

This invention relates to an improved hand operated load lifting device which has been devised for lifting and also for transporting, with a minimum of manual effort, general merchandise of a heavy nature, such as filled oil drums, packing cases, and the like.

The invention has been more particularly devised for the purpose of handling drums filled with petrol or lubricating oil, and is especially suitable for use in motor garages, service stations, engineering shops and the like, where it has been found that filled oil drums, such as those of 40 gallon capacity, are cumbersome and difficulty is experienced in conveniently handling same.

Moreover, by means of this invention, an oil drum can, with little manual effort, be elevated from a vertical to a horizontal position above the ground, enabling the contents thereof to be decanted and drained without the employment of a pump or like decanting means, which is necessary when the drum is upended or is in a vertical position upon the ground.

The invention resides in the provision of a skeleton frame or load support furnished at its underside and front portion with curved or arcuate members which latter are adapted to have rolling contact with the ground, and by means of a pair of handles secured to or forming part of the rear end of said frame, the latter can be readily rolled or tilted over from the horizontal into a vertical position against the load to be handled.

Suitable means are provided for securing the load to the frame, when in the vertical position, and upon exerting rearward and downward pressure upon the frame handles, the loaded frame is with little effort rolled or tilted back into the horizontal position, and at the same time the load is raised to the height desired, as the curved or arcuate members having rolling contact with the ground as aforesaid, act as movable fulcrums when leverage is applied to the frame handles.

The invention will now be fully described with reference to the accompanying sheets of drawing, in which,

Fig. 1 represents a sectional longitudinal elevation of a device, constructed according

to this invention, and especially adapted for lifting filled oil drums and the like.

Fig. 2 is a plan of Fig. 1.

Fig. 3 is a side elevation of the device, showing same in a vertical position and with an oil drum attached thereto for being elevated.

Fig. 4 is a side elevation, showing the device and its load tilted slightly rearwards to enable its curved members to roll upon the ground and to raise the load bringing the loaded frame into the horizontal position.

Fig. 5 is a side elevation showing the loaded frame brought into the horizontal position.

Fig. 6 is an end elevation of Fig. 5.

Fig. 7 is a detail plan view of the lifting device.

Fig. 8 shows the device in the loading position for handling a packing case, and

Fig. 9 is a detail front view of the frame, showing same provided with a lip for supporting one end of a packing case.

Referring more particularly to Figs. 1, 2, 3 and 4 of the drawing, 1 denotes the side members of a skeleton frame, which members consist of angle iron beams spaced apart by means of concave bars 2 secured by bolts, 3 to the side members of the frame. The frame is furnished with a pair of handles 5 connected together by a transverse rod 6, and may be hingedly supported upon a transverse rod 7, secured to the side members 1 of the frame. The downward pivotal movement of the handles 5 is limited by lugs 8 bolted to the side members 1. By this arrangement, the handles 5 may be thrown upwardly and forwardly to rest upon the frame when the latter is not in use.

When the frame is in the vertical position, as shown in Fig. 3, the lowermost concave bar 2 is adapted to be positioned under the lower rib *a* of the filled oil drum *A*, so as to support its weight during the tilting of the frame rearwards, as shown in Fig. 4, both the concave bars 2 providing a supporting cradle for the oil drum when in its horizontal position, as shown in Fig. 5.

As shown in the drawings, the underside

and the forward portion of the lifting frame is provided with a pair of curved or arcuate supporting members 9. The curvature of each supporting member 9 may take the form 5 of a cam, or of an arc closely approximating to a quadrant, in order that the curved surfaces of the said members will have free rolling movements upon the ground.

The outer extremities of the curved members 9 are bent inwardly in order to be secured by bolts 10 to the side members 1 of the frame, and the inner extremities of the curved portions of the members are bent upwardly to provide straight portions 9^a which 10 are secured by bolts 10^a to the frame members 1. 11 are transverse bars which are secured to the members 9 to strengthen the latter. Diagonal stays 12 are secured to each of the vertical or straight portions 9^a of the members 9 in order to increase the rigidity of 15 same.

13 are inclined stays, the upper ends of which are secured by bolts 14 to the frame members 1, and the lower ends of said stays 20 are suitably bent in order to be secured by bolts 15 to the straight portions 9^a of the curved members 9, and are formed with bearings 16 to support an axle 17, upon which a 25 pair of travelling wheels 18 are mounted.

30 A pair of legs 19 are secured to the inclined stays 13 to enable the frame and its load to be rigidly supported in the horizontal position, as shown in Figs. 1 and 5. If desired, legs or props 19^a may be hinged to 35 the front of the lifting frame to furnish additional supports for the load when elevated. 20 is a frame which pivots upon a cross bar 21 secured to the side members 1, and to 40 which frame a dog or hooked member 22 is adjustably bolted in order to grip the flanged 45 end of the oil drum and to assist in securing the drum to the lifting frame, the length adjustment of the said hooked member permitting it to be employed on drums of different diameters.

50 In Fig. 5 the oil drum A is shown retained upon the lifting frame by means of a pair of chains 23, and wherein one end of each chain is attached to an eye bolt 24, secured to one 55 of the side members of the lifting frame, the free end of the chain after passing about the drum being inserted and retained in a slotted bracket 25, secured to the other side member of the frame. If desired the travelling wheels 18 may be dispensed with, when 60 transportation of the drum is not required, and in Figs. 5, 6 and 7, the frame is shown with the wheels removed therefrom. Also in Fig. 7, adjustment bolt holes 4 are shown 65 formed in the side members 1 of the lifting frame to enable the positions of the concave bars to be adjusted relatively to the ribs a on the oil drums.

65 In Fig. 8, the lifting frame is shown in its vertical position and against a packing case

B, which is required to be loaded upon the frame and to be elevated. The front end of the frame is provided with a lip 26 bolted to a pair of angle brackets 27 which are detachably secured by bolts 28 to the front ends 70 of the side members 1. The lip is employed to slide or to be passed underneath the bottom of the upended packing case to enable the lifting frame to support the weight of the case. When not required the lip 26 and the supporting brackets may be detached from the frame by removing the bolts 28.

75 Chains 29 are also employed to secure the packing case to the lifting frame, said chains being furnished with gripping hooks 30 80 which are used to retain the case to the frame.

In operating the device, the lifting frame is brought into a vertical position and against the upended oil drum, packing case or load, as shown in Figs. 3 or 8, whereupon the load 85 is secured to the frame by the means hereinbefore described. The operator then grasps the handles 5, and exerts a downward and backward pressure thereon, and if necessary, and in order to obtain additional leverage, 90 stands or exerts foot pressure upon one of the cross bars 11, or upon the axle 17.

95 When tilted approximately into the position indicated in Fig. 4, and owing to the rolling contact of the curved members 9 upon the ground, comparatively little continued pressure upon the handles 5 is required to raise the load by bringing the loaded frame into the position shown in Fig. 5, part of the weight 100 of the load also acting as a counter balance to bring the frame into such position. The weight of the loaded frame is then transferred from the curved members 9 to the wheels 8—if a wheeled frame is employed—thus enabling the load to be transported as required. 105 The loaded frame is finally brought to rest upon the front legs 19, or upon the latter and the rear legs 19^a enabling the oil drum, if such constitutes the load, to be conveniently 110 decanted.

I claim:—

115 1. A hand operated load lifting device for elevating cylindrical containers such as oil drums or the like having an exterior circumferential rib therearound, comprising a rectangular frame including spaced, longitudinally disposed side bars, curved members secured to the under side of said frame at and disposed rearwardly from the forward end of said frame and having rolling contact with the ground, the forward end of said frame 120 forwardly and upwardly unobstructed, and a transverse bar adjustably mounted across and between said frame side bars spaced inwardly a distance from the frame forward end, said transverse bar shaped to fit over and around a cylindrical container and engage beneath the exterior rib of such a container in 125 order to support the container when being elevated by the load lifting device to a horizontal position.

zontal and elevated position on and with said frame.

2. A hand operated load lifting frame for elevating cylindrical containers such as oil drums and the like having an exterior circumferential rib therearound spaced inwardly from the ends thereof, comprising a rectangular frame including spaced longitudinally disposed frame side members, means at the forward end of the frame having rolling contact with the ground on which the frame is swingable to and from vertical container engaging and elevating position, handle members at the rear hand of the frame for swinging the same on said forward end means, and spaced transverse concave bars adjustably mounted upon said frame across and between the side members thereof, the transverse concave bars adjacent the frame forward end spaced inwardly a distance from such end and adapted to fit around a vertically disposed container engaged beneath the container rib to support the container when being elevated and tilted by the load lifting device from vertical to horizontal position, the frame and transverse concave bars forming a supporting cradle for the container in horizontal elevated position.

In testimony whereof I have signed my name to this specification at Melbourne, Victoria this 30th day of October, 1928.

JOHN BATES.
